UNITED STATES PATENT OFFICE.

WILLIAM EDWARD SMITH, OF WASHINGTON, DISTRICT OF COLUMBIA.

DESIGN FOR A BICYCLE-FRAME.

SPECIFICATION forming part of Design No. 18,746, dated November 20, 1888.

Application filed June 19, 1888. Serial No. 277,594. Term of patent 31 years.

To all whom it may concern:

Be it known that I, WILLIAM EDWARD SMITH, of Washington, in the District of Columbia, have invented a new and original Design for Bicycles, of which the following is a specification.

My design for a bicycle-frame is clearly illustrated in the accompanying drawing, which represents said frame in perspective, 10 the wheels, crank-shaft, and other parts with which it is used being omitted in the drawing.

A represents a front member, having the lower end forked and curved forward and its upper end made of cylindrical form and joined 15 at the top to a cross bar or handle, B, of the form shown.

The reach or body portion of the frame C comprises the upright cylindrical portion a, the portion b, curved thence downward and 20 rearward, and the portion c, joined at its forward end to the lower portion of the part b and extended thence rearward with a slight upward inclination, its rear end being forked or divided vertically into two arms, as shown. 25 The forward end of the portion c and the part b are of cylindrical form in cross-section, and they are joined at substantially right angles,

or in such manner as to leave a sharp angle at their point of union. The cylindrical standard rises from the part c just forward of its 30 divided portion, as shown. An arm or brace, d, extends from the upper end of the portion a to the lower part of the portion b. This is not an essential feature.

The striking or essential features of my design are the forked portion c, joined at a sharp angle to the lower end of the portion b, and the front forked portion joined to the front upper end of the portion b.

What I claim as my design is—

The design for a bicycle-frame, as herein described and shown, comprising the forked member A, the member b, curving thence downward, and the member c, forked at its rear end and joined at its forward end at a 45 sharp angle to the lower end of member b.

In testimony whereof I hereunto set my hand, this 18th day of April, 1888, in the presence of two attesting witnesses.

WILLIAM EDWARD SMITH.
